UNITED STATES PATENT OFFICE.

FRIEDRICH SCHWARZ AND HEINRICH TAUSS, OF VIENNA, AUSTRIA-HUNGARY

SYRINGE.

974,531.

Specification of Letters Patent. Patented Nov. 1, 1910.

Application filed January 13, 1908. Serial No. 472,074.

To all whom it may concern:

Be it known that we, FRIEDRICH SCHWARZ, a subject of the Emperor of Austria-Hungary, residing at 119 Mariahilferstrasse VI, Vienna, Austria-Hungary, and HEINRICH TAUSS, a subject of the Emperor of Austria-Hungary, residing at 24 Schlossgasse VIII, Vienna, Austria-Hungary, have invented new and useful Improvements in 10 Syringes, of which the following is a specification.

This invention relates to improvements in hypodermic syringes.

An object of the invention is to provide a 15 container, which may easily be sterilized, and which may be kept tightly closed until the time of injection.

Another object of the invention is to provide a hypodermic needle, which at a desired moment opens said container and penetrates thereinto to a certain depth.

In the drawing, Figure 1 is a vertical section through the container. Fig. 2 is a similar section through a part connected 25 with the needle, showing the needle itself in elevation.

The container *a* preferably in the shape of an inverted vial, may be made of hard material as glass, hard rubber or such like. It 30 is closed at the wider portion *c* by means of a thin membrane *b* of soft, resilient material for instance soft rubber, caoutchouc. The membrane is tightly pressed to the edge of the vial by means of the hard rubber plate 35 *d*, a projecting cylindrical flange on said plate serving as protection for the wider portion of the vial and the membrane. The plate *d* is provided with a preferably 40 central aperture *t*, into which the neck of a compressor bulb *u* or some similar device is fitted. When the vial is filled with serum or some other injection liquid, then any 45 pressure exerted by the bulb *u* upon the membrane *b* will bend the membrane toward the interior of the vial and expel some liquid through the neck like narrow portion thereof. A nipple *i* is placed over the narrow portion or neck of the container, the wall of the orifice in the nipple being 50 shaped to fit the outside surface of said neck. At its top the nipple *i* is provided with an annular flange *h*. A portion below the flange is provided with an external screw thread, the portion of the nipple adjacent the screw threaded portion being of 55 somewhat smaller diameter. A thin plate *l*

of hard, easily sterilizable material serves as closing member for the vial and the nipple; a cap *k* being provided with a small central aperture, is then pushed over the reduced portion of the nipple tightly fitting thereon, and serves to hold plate *l* in place. A cap nut *m* engaging with its thread the threaded portion of the nipple *i* is the cover 60 of the cap *k*, said nut being likewise provided with a central aperture *o*. A tinfoil plate *n* may be placed between the nut *m* and the cap *k*.

For the purpose of making the entire structure self contained the closing members at the wider portion of the container are attached to the closing members at the neck by means of a plurality of rods *g*, which pass through approximately circumferential apertures in the flange *h* of the 75 nipple *i*, and which are secured in these apertures, the ends of the rods being provided with preferably integral head-like portions. The rods are bent to follow the outline of the vial, their upper ends being 80 threaded, and extending into circumferentially arranged apertures in a plate *e*. This annular plate is placed on top of the cover plate *d* and is centered by a cylindrical boss projecting from the top surface of said 85 plate. A plurality of bolts *f* provided with internal thread project through the apertures in the plate *e* engage the threaded ends of the rods *g*, and in tightening these bolts, the plate *d* and nipple *i* are drawn toward 90 each other, providing thereby tight and secure closing means. The hypodermic needle *r* is hollow and preferably tapered. Near its rear end *q* it is provided with a laterally 95 extending flange *p*, the rear portion of the needle projecting beyond this flange and being suitably pointed at *s*.

The container may be filled in the laboratory, and the closing members secured thereto and to each other by means of the rods *g* and bolts *f*. The rear end *q* of the needle does not come in contact with the liquid until the cap nut *m* is tightened on the nipple *i*, and said rear end is also prevented from contact with the outer air through the tinfoil 100 plate *n*. When it is desired to use the syringe then the cap nut *m* is drawn onto the nipple *i*; the flange *p* of the needle is in engagement with said cap nut, and the point *s* is forced through the tinfoil plate *n* 110 and the plate *l* into the liquid. Any pressure exerted upon the membrane *b* will bend

the same toward the interior of the container and expel a corresponding amount of liquid through the needle.

We claim:

5. 1. A hypodermic syringe comprising in combination a rigid container, a detachable membrane providing a closing means for said container at one end, detachable closing members for the other end thereof, 10 means for fastening said membrane and closing members onto said container, said means serving simultaneously for securing said membrane and closing members to each other, a hypodermic needle, and a device for 15 exerting a pressure upon said membrane.
2. A hypodermic syringe comprising in combination a container, a membrane closing said container at one end thereof, a

plate covering said membrane, a second plate closing the other end of said container, 20 a nipple engaging said second plate, a plurality of rods extending from said nipple, said rods being provided with screw threads, a plurality of bolts projecting through the first named plate and engaging 25 the threads on said rods, a hypodermic needle provided with a flange near its rear end, and a device for exerting a pressure upon said membrane.

In testimony whereof we affix our signatures in presence of two witnesses.

FRIEDRICH SCHWARZ.
HEINRICH TAUSS.
